CLAIM

The ornamental design for a crane cab, as shown and described.

DESCRIPTION

FIG. 1 is a front elevational view of a crane cab showing our new design;

FIG. 2 is a bottom plan view of the crane cab;

FIG. 3 is a top plan view of the crane cab;

FIG. 4 is a left side elevational view of the crane cab;

FIG. 5 is a top sectional view of the crane cab showing the interior of the crane cab;

FIG. 6 is a bottom plan view of an interior ceiling of the crane cab;

FIG. 7 is a top left perspective view of the crane cab; and,

FIG. 8 is a top right perspective view of the crane cab.

The broken lines showing of elements of the cab or a portion thereof form no part of the claimed design.

1 Claim, 8 Drawing Sheets
